UNITED STATES PATENT OFFICE.

JESSE T. SHEETS, OF COVINGTON, KENTUCKY.

AMBULANCE STRETCHER-SUPPORT.

1,170,688.

Specification of Letters Patent.

Patented Feb. 8, 1916.

Application filed October 23, 1912. Serial No. 727,278.

To all whom it may concern:

Be it known that I, JESSE T. SHEETS, a citizen of the United States of America, and resident of Covington, county of Kenton, 5 and State of Kentucky, have invented certain new and useful Improvements in Ambulance Stretcher-Supports, of which the following is a specification.

This invention relates to stretcher supports for ambulances, or similar vehicles, and has for an object to produce a new and improved support, which simplifies the operation of lifting a patient into, and removing one from, an ambulance.

10 A further object is to produce a stretcher support which eliminates the necessity of an attendant entering the ambulance for the purpose of mounting a stretcher in the proper position on its support within the 15 ambulance.

These and other objects I attain by means of an apparatus embodying the features herein described, and illustrated in the drawings accompanying and forming a part 20 of this application.

In the drawings, Figure 1 is a perspective view of a support embodying my invention. Fig. 2 is a somewhat diagrammatic, fragmental sectional view of an ambulance equipped with a stretcher support embodying my invention. The support is shown in the position it occupies during the operation of placing a patient in, or removing one from, the ambulance. Fig. 3 is a 30 fragmental end view of an ambulance equipped with a support similar to the one shown in Fig. 2, the support being shown in the normal or stretcher-supporting position. Fig. 4 is a view of the inner end of 35 the support, shown in Fig. 3, on an enlarged scale, and with portions broken away for convenience of illustration.

The apparatus shown in Figs. 2, 3, and 4 is equipped to receive a single stretcher, 5 while the support shown in Fig. 1 is capable of accommodating two stretchers. The support illustrated as an embodiment of my invention, may be employed in an ambulance or similar vehicle and is so constructed 10 that it may be quickly and easily assembled and secured in place in the ambulance, and as easily and rapidly dismantled and

removed from the ambulance. The support includes a frame 5, which is capable of being moved from a horizontal or normal position, to an inclined or stretcher receiving or delivering position, such as is illustrated in Fig. 2. A movable stretcher-engaging member or holder 6, for engaging one end of a stretcher, is so mounted on the frame 55 that it is capable of being moved longitudinally thereof, and of being turned to different positions, relatively thereto, for the purpose of simplifying the operation of placing a stretcher in the proper position within the 60 ambulance or of removing a stretcher from the ambulance. Stretcher supports, ordinarily employed, are so formed and so located within the ambulance, that it is necessary for one or both of the attendants bearing the stretcher, to enter the ambulance for the purpose of mounting the stretcher in the proper position on the supports. This is a difficult operation, when a patient is on the 65 stretcher, and the operation of removing a patient from the ambulance is equally difficult. The steps provided on the rear end of the ambulance are usually steep and it is difficult for the attendant, carrying the head 70 end of the stretcher, to enter the ambulance 75 and place the stretcher in the proper position on its supports. This difficulty is entirely overcome with my invention by mounting the stretcher-engaging member or holder 6 on a way of guide 7, which is so located on the frame 5 that the member 6 is capable of being moved to a position at one 80 end of the frame, such that it clears the uprights of the frame and is accessible from the exterior of the ambulance. 85

In the embodiments of my invention herein illustrated, the movable frame 5 aids in the operation of placing a stretcher, with a patient on it, in, or removing it from, the ambulance, since it is capable of being 90 moved so that it projects out of the rear end of the ambulance, and it consequently permits the member 6 to be moved to more accessible positions, than would be the case if the frame were stationary.

100 The frame illustrated is formed of pipe sections and is so arranged that it can be folded up so that it occupies a small amount of space. It will be understood, however,

that the pipe sections are employed merely for the purpose of lightening and cheapening the construction, and that the frame may be otherwise constructed.

5 The base portion of the frame is rectangular in shape, and is provided at the outer end with projecting handles 8, and yieldingly mounted feet 9, which, as illustrated, are secured to the frame by means of intermediate supporting springs. Uprights 10—11 are located at the outer end of the base portion, and as shown, are formed of a single piece of piping, which is bent to a substantially U-shaped form, and is provided, at its lower ends, with T-sections 12, each of which is loosely or rotatively mounted on a projection, formed on the base portion, so that the uprights can be lowered to a horizontal position during the operation 20 of folding up the support. Any suitable means, such for example as bolts 13—which extend through apertures formed in the T-sections and the extensions, on which the sections are mounted—may be employed for 25 holding the uprights 11 in the vertical position.

A single upright 14 is located at the inner end of the support. This upright, like each of the uprights 11, is provided at its lower 30 end with a T-section 15 which is loosely or rotatively mounted on the base portion of the frame, so that the upright is capable of being turned downwardly, to a horizontal position, in folding up the support. As 35 shown, the guide or way 7, for the holder or stretcher-engaging member 6, consists of a pipe section, or rod, which is bent back upon itself, at the outer end of the support and is secured to the uprights 12 in 40 such a way, that it projects outwardly past them.

The inner end of the rod or way 7 is so mounted on the upright 14 that the stretcher holder 6 is yieldingly supported, 45 when located at the inner end of the frame or adjacent to the upright 14. This is accomplished in the apparatus illustrated, by providing a supporting yoke 14' for the inner end of the way 7, which is yieldingly 50 mounted on the upper end of the upright 14. The yoke has a shank or plunger 16, which projects into the upper end of the upright 14 and is surrounded by a coil spring 17. The spring 17 supports the yoke, 55 and any suitable means may be employed for securing it to the upright and to the yoke, for the purpose of preventing the yoke from being accidentally disengaged from the upright when the frame is folded.

60 In the drawings I have shown a removable bolt 18 which projects through apertures formed in the way 7 and in the yoke 14', and locks the way in place on the yoke, and consequently locks the way to the up-

right 14. The looped end of the way is 65 also removably but positively secured to the uprights 11. In the illustrated apparatus this is accomplished by rigidly mounting a T-section 19 on the uprights 11, so that its open end is capable of receiving the 70 looped end of the way 7. Any suitable means, such for example as a removable bolt or pin, may be employed for securing the end of the way to the pipe section. The locking of the way 7 to the uprights 11 and 75 14 locks the frame in the upright position and holds it rigidly in that position.

The holder or stretcher-engaging member 6 is substantially U-shaped and is mounted on the way 7 by means of a pulley 21 to 80 which it is connected by means of a swivel pin 22. With this arrangement the member 6 is capable of being moved along the way 7 and also of being turned to different angular positions relatively to the way. The 85 member 6 is of such width that it readily passes between the uprights 11, and the looped back portion of the way 7 enables it to be moved to such a position on the support and outside of the uprights 11, that 90 it can be turned at right angles to the plane of the members 11 for the purpose of being more easily secured to the head end of a stretcher. The uprights 11 are provided with brackets 23 which operate to support 95 the foot of the stretcher.

The frame 5 is preferably mounted on rollers 24, so that it can be readily moved to an inclined position in which it projects beyond the rear end of the ambulance in 10 which it is located. As illustrated, the rollers 24 are mounted on a board or strip 25 which extends transversely across the floor of the ambulance and may be removably secured in place by means of a bolt 26. 10 Each roller 24 is so positioned that it engages one of the side or longitudinally extending members of the base portion of the frame, and it is provided with a concave groove in its peripheral face, which receives 11 one of the side members and guides the longitudinal motion of the frame. I have also provided means for limiting the motion of the frame and for preventing it from tilting an objectionable amount when it is moved 11 to the inclined position. As illustrated, this means consists of hooks 27 which are adjustably mounted on the support blocks of the rollers 24 and which project over the side members of the base portion of the 12 frame, so that they are in a position to engage and check the motion of the members in case the members move upwardly from the rollers, or the frame tilts too much, when in the inclined position. The hooks 12 may also be so formed and located that they will engage the inner end member of the base portion of the frame and thereby

prevent the frame from being pulled off of the rollers during the operation of moving it to the inclined position.

The operation of mounting a stretcher on a support embodying my invention is somewhat as follows: The outer end of the support is lifted by means of the handles 8, so as to raise the feet 9 off of the bottom of the ambulance. The support is then pulled forward so that it extends beyond the rear end of the ambulance, and so that the feet are moved to a position beyond the rear edge of the floor. The outer end of the support is then set down so that the side members of the base portion rest upon the floor or the rear edge of the floor of the ambulance. This causes the frame to occupy an inclined position, as illustrated in Fig. 2. The member 6 is then moved to the outer end of the way 7 and is turned at right angles to the plane of the uprights 11, so that the head end of a stretcher can be readily secured to it. The attendant bearing the head end of the stretcher then sets the stretcher on hooks formed on the member 6, and the attendant, bearing the foot of the stretcher, walks around so as to turn the stretcher about the swivel pin 22 of the member 6. When the stretcher is turned to a position such that it extends longitudinally of the support the attendant pushes the stretcher between the uprights 11 and thereby causes the pulley 21 to ride along the way 7 and the members 6 to move to a position at the inner end of 35 the holder, adjacent to the upright 14. The foot of the stretcher is then mounted on the brackets 23, which places the stretcher wholly on the support and also locks it against longitudinal motion. After the 40 stretcher is in place on the support the outer end of the support is raised, by means of the handles 8, and is moved to the normal position within the ambulance, such that its feet 9 engage the floor of the ambulance. The 45 springs of the feet 9 yield sufficiently to prevent the foot of the stretcher being subjected to shocks and jolts occasioned by the motion of the vehicle, and the spring 17, together with the loop formed in the way 7, permits 50 the head of the stretcher to yield sufficiently to cause the stretcher to ride comfortably. The T-section 15 to which the upright 14 is secured is capable of turning about its mounting member so that the upright 15 can 55 sway to accommodate itself to the motion of the inner end of the way 7, occasioned by the yielding of the spring 17.

The operation of removing a stretcher from the support is the reverse of that just 60 described: The support is first moved to the inclined position, the foot of the stretcher is lifted off of the bracket 23 and the stretcher is moved outwardly, longitudinally of the support, to such a position that its head

clears the uprights 11. The stretcher is then 65 turned to a position at right angles to the support, so that its handles, located at the head end, are easily accessible and the second attendant then grasps the handles and lifts the head of the stretcher off of the 70 member 6. In the drawings I have shown the member 6 so constructed that they are adapted to engage a transverse member 28, located between the longitudinal members 75 or handles of the stretcher. It will of course be understood that the member may be provided with hooks of any desired shape, capable of engaging the handles or other portions of the stretcher, if desired.

In Fig. 1 I have shown a modification of 80 my invention, in which the support is equipped with two movable stretcher-engaging members. In addition to the member 6, a member 29 is mounted on the way 7 and is capable of being moved along the way for 85 the purpose of receiving the head end of a stretcher. Two sets of brackets 23 are also mounted on the uprights 11. The member 29 is similar to the member 6, described, except that its stretcher-engaging arms are 90 shorter. In placing two stretchers on the support illustrated in Fig. 1, the bottom stretcher must be located in position on the support, prior to mounting the second 95 stretcher on the support, and the upper stretcher must be removed from the support before the lower stretcher is removed.

The operation of folding the stretcher support, illustrated in Fig. 1, is somewhat 100 as follows: The way 7 is first detached and removed from the uprights 11 and 14. This also removes the members 6 and 29 from the support and they can easily be removed from the way 7 by merely slipping them off of its inner end. Then the removable bolts 105 13 are withdrawn so as to permit the uprights 11 to swing to a horizontal position against the base portion of the frame, and the upright 14 is turned to the horizontal position, so that it rests on the uprights 11. 110 The members 6 and 29 and the way 7 may then be strapped onto the folded frame portion for the purpose of keeping all of the parts together. The frame portion may be removed from the ambulance by turning the 115 hooks 27 to such positions that they free the base portion of the frame and then by lifting the frame off of the rollers 24. The rollers 24 may also be removed from the 120 floor of the ambulance by simply withdrawing the holding bolts 26, and removing the strip 25.

The operation of unfolding and assembling the different parts of the support is 125 as simple as that of dismantling and folding up the support. The upright 14 is first raised to the vertical position, the uprights 11 are then raised to the upright position

and secured in place by means of the bolts 13. The looped end of the way 7 is then secured on the uprights 11 and the members 6 and 29 are placed on the way. The inner 5 end of the way is then secured to the yoke 14' by means of the bolt 18. The operation of folding up, and unfolding the stretcher support, illustrated in Figs. 2, 3 and 4 is substantially the same as that of the support 10 illustrated in Fig. 1. Inasmuch as two stretchers are seldom employed in an ambulance it may be desirable to so construct the pulley support of the member 29, that the member 29 can be hooked onto the way 7 15 without the necessity of first removing the member 6 from the inner end of the way. With such an arrangement the support may be easily converted so that it will support either one or two stretchers.

20 In accordance with the United States patent statutes, I have illustrated the two embodiments of my invention, but I desire it to be understood that various changes, modifications and substitutions may be made in 25 the details of construction of the apparatus illustrated without departing from the spirit and scope of my invention as set forth by the appended claims.

What I claim is:

- 30 1. In combination with an ambulance, a stretcher support comprising, a frame located in the ambulance and movable from a horizontal to an inclined position, and a stretcher-engaging member mounted on and 35 movable longitudinally along said frame.
2. In combination with an ambulance, a stretcher support comprising, a frame movably mounted within the ambulance, a way mounted on the frame and projecting at one 40 end beyond its supporting members, a stretcher-engaging member mounted on the way and movable therealong to a position beyond the end members of the frame, means provided on the frame for supporting 45 one end on the floor of the ambulance and means mounted on the floor of the ambulance for supporting the other end of the frame.
3. In combination with an ambulance, a 50 stretcher support comprising, a frame mounted in the ambulance and movable, relatively thereto, to a horizontal or inclined position, a way mounted on the frame and projecting at one end beyond the end members of the frame, a stretcher-engaging 55 member mounted on and movable along the way, rollers mounted on the floor of the ambulance for supporting one end of the frame and means formed on the other end of the frame for coöperating with said rollers to 60 support the frame in a horizontal position.
4. In combination with an ambulance, a 65 stretcher support comprising, a frame movably mounted within the ambulance, a way mounted on the frame and projecting be-

yond its support members at one end of the 65 frame, a stretcher support member mounted on, movable along and capable of being turned to angular positions relatively to said way, means mounted on the floor of the 70 ambulance for supporting one end of the frame and means secured to the frame for supporting the other end of the frame.

5. A stretcher support comprising, a frame, a way mounted on the frame and projecting at one end beyond the end members of the frame, a movable stretcher-engaging member mounted on and movable longitudinally along the way and means mounted on the frame for coöperating with said member in supporting a stretcher on the 80 frame.

6. A stretcher support comprising, a frame having a way formed thereon, which extends at one end beyond its supporting members, a stretcher-engaging member 85 mounted on, movable along, and capable of being turned to angular positions relatively to the way, and means mounted on the frame for coöperating with said member in supporting a stretcher.

7. A stretcher support comprising, a frame consisting of a base portion, uprights capable of being folded to horizontal positions along said base portion, a way removably mounted on said uprights and a 95 stretcher-engaging member movable along said way.

8. A stretcher support comprising, a frame having two sets of stretcher-engaging brackets located one above the other, a way 100 mounted on the frame above said brackets, and two stretcher-engaging members mounted on and movable along said way.

9. A stretcher support for ambulances comprising, a frame having a way formed 105 thereon and projecting at one end beyond the end members of the frame, two sets of stretcher-engaging brackets located on said frame, one above the other and below said way, and two stretcher-engaging members 110 of different lengths mounted on and movable along said way.

10. A stretcher support comprising, a frame, a way secured to the frame, means mounted on the frame for yieldingly supporting one end of the way, spring feet for supporting one end of the frame and a stretcher-engaging member mounted on and movable along the way.

11. A stretcher support comprising, a 120 frame, a way mounted on and projecting, at one end, beyond the end members of the frame, means for yieldingly supporting the other end of the way on the frame, and a stretcher-engaging member mounted on and 125 movable along the way.

12. In combination with an ambulance, a stretcher support comprising a frame,

stretcher engaging brackets mounted on the frame, a way mounted on the frame and projecting at one end beyond the end members of the frame, a stretcher adapted to engage said brackets and said way, said stretcher being movable along the way to the projecting portion thereof when it is lifted from said brackets.

In testimony whereof, I have hereunto subscribed my name this eighteenth day of 10 October, 1912.
